UNITED STATES PATENT OFFICE.

JEAN MARTIAL LOBIT, OF BROOKLYN, NEW YORK.

MOLD FOR LINE-CASTING MACHINES.

Application filed February 20, 1925. Serial No. 10,463.

This invention relates to line-casting machines and more particularly to the alining of the matrices in front of the mold.

With the molds in general use it is impossible to cast a slug that will print letters of different size all of which will be alined at their feet.

If it be attempted to use several letters of varying height in one line, the result would be that all of these letters would be alined along their tops and therefore the practice is not followed. However it is often desirable to use letters of different sizes and among the objects of this invention is to provide a mold capable of casting a slug having thereon letters of different height alined at their feet.

Another object is to provide a manner of suitably adjusting the length of a slug.

Other objects involving novel constructions and combinations of parts will appear in the specification, and in the claims thereof setting forth a preferred embodiment of my invention which will be fully understood from the detailed description and drawings, in which:

Fig. 1 is a front view of the mold disk and two molds.

Fig. 2 is a section of Fig. 1 on line 2—2.

Fig. 3 is a front view of the mold for casting ordinary type.

Fig. 4 is a section of Fig. 3 on line 4—4, showing the liners.

Fig. 5 is a section through Fig. 3 on line 5—5 illustrating the mode of securing the liners in position.

Fig. 6 shows in perspective an aliner rail block for large type.

Fig. 7 is a sectional view on line 7—7 of Fig. 1, illustrating the rail block releasing screws.

Fig. 8 is a sectional view on line 8—8 of Fig. 1.

Fig. 9 is a filler bar.

Fig. 10 shows a detail of the mold assembling locking means.

Fig. 11 is the right liner for the large type mold;

Fig. 12 is the adjustable liner for the same mold.

Fig. 13 is an end view of the mold showing a matrix in position with its upper letter opposite the mold slot.

Fig. 14 is a similar view showing the matrix in position with its center letter opposite the mold slot.

Fig. 15 illustrates the three different forms of types carried on one matrix.

Fig. 16 illustrates the position of a large type matrix against a large type rail block.

Fig. 17 is a similar view of a larger type matrix against the same type rail block.

Fig. 18 is a sample of a slug having different sized type lined up on a line of feet.

Ordinarily the mold disk 1 has mounted thereon a plurality of molds which are adjustable in turn to a position in front of the mold slot by means of a turning knob 2 and pinion 3. In my disclosure I have illustrated two molds; the upper one in Fig. 1 being for ordinary type, and the lower one being for large type. Each mold has a right angle member having one flange 4 securely fastened to the disk by screws 5 while the other flange extends out perpendicular thereto and forms the capping piece 6 of the mold. The lower face of this piece is the datum line parallel to which the feet of letters of all sizes are dressed.

Just below each mold there is located a bar 7 secured to disk 1 by screws 8. This bar serves the purpose of supporting rail block 9 and has passing through it for this purpose a plurality of screws 10 each having a spring 11 under compression and constantly tending to raise the rail block. The lower end of each spring bears against the bottom of hole 12 in member 7 while the upper end bears against a recess in rail block 9. The threaded end of the screw is screwed into a tapped hole 13 in the rail block and as the screw is unscrewed springs 11 will elevate rail block 9.

The rail block 9 must be kept at or very close to a constant distance from the mold caps 6 for a selected set of matrices and this is accomplished by liners 14 and 15 and a filler 16, if such be necessary. These liners are of a definite length and the right hand one always has its left edge at the zero mark of the length of the line scale on flange 4, while the left hand one may be positioned along its length in order to limit the length of slug to be cast. The depth of these liners depends upon the size of the type to be used. As is very often the case, the constant distance between the top of the rail block and the mold cap is greater than the depth of slug that is to be cast so I provide a filler bar 16, Figs. 3 and 9, to take up the difference created. Upon changing the size of type to

a lower point a filler bar of correspondingly greater depth must be inserted.

For compactly securing the liners, filler bar and rail block in a definite position relative to the disk 1, there are provided locking members 17, Figs. 5 and 10, each having two pins 18 and a knob 19 to facilitate handling. These pins pass through holes in the respective members and when the locking members 17 are in place they are secured by a latch 20 pivoted at 21 which is swung down and over the top of them.

The adjustment in the length of line of type to be cast is made by moving liner 15 in which there are six holes to the inch allowing for a variation in length of one em. In order to be able to change the length of a line by one half an em, four holes to the inch are provided in the left hand end of filler bar 16 and rail block 9, and the half em variations are obtained by passing the pins through various combinations of holes in the liner and of the superposed holes in the filler and rail block. It is obvious that other combinations of holes could be provided to allow for a shorter change in length of line if such would be desired.

Three rails 22 are provided and, with any one of which, matrix 23 may be alined by its ear 24. Should the matrices be alined against the lower rail as shown in Fig. 13, the upper type on each matrix would be cast, and, if it should be alined against the center rail as shown in Fig. 14, the center type would be cast. Thus it is possible by the use of the three rails to bring any of the three different type carried by one matrix, Fig. 15, opposite the mold slot and cast a line having any arrangement desired of these three type.

The matrix used may have any desired number and variety of type and I have proposed the use of one having three type of the same size allowing for selectivity of either a roman, full-faced, or italic letter (Fig. 15). Each of these letters are positioned on each matrix so that whichever one is chosen to cast a letter in a line on a slug, it will be dressed with the other letters of the line on a line of feet as shown in Fig. 18.

Since the rail block and its rails are always kept at a constant distance from mold cap 6 by the use of liners and a filler bar, the letters will always be alined along their feet and several sizes of type may be cast in proper alinement as shown in Fig. 18.

The lower mold for large type as illustrated in Figs. 1, 7, 8, 16 and 17, is substantially the same as the mold for ordinary type, above described. The rail block 9' has a single rail 22' and the top of the block extends nearly to the lower surface of mold cap 6. The shape of the block requires the use of two liners having narrow retaining

edges 25 and deep fronts 26, but holes similar to those in liners 14 and 15 are used (Figs. 11 and 12).

As illustrated in Figs. 16 and 17, matrices of various type sizes may be alined for printing a line of type with the result that all of the type are alined on a line of feet as shown in Fig. 18.

My invention is capable of a wide variation and relationship of parts without departure from the nature and principle thereof and I do not restrict myself unessentially in the foregoing or other particulars, but contemplate such alterations and modifications within the scope of the appended claims as may be found to be advisable.

What I claim is:

1. In a machine of the class described, the combination of a mold disk, a mold cap permanently fixed to said disk, a rail block, supporting means for said rail block, and means intermediate said mold cap and rail block for determining the size of a slug.
2. In a machine of the class described, the combination of a fixed piece against which slugs are cast, liners for determining the size of a slug, an alining rail block, and a filler for maintaining said alining block at a constant distance from said fixed piece.
3. In a machine of the class described, the combination of a fixed piece at the top of a mold, a movable aliner means, means constantly urging said aliner means toward said fixed piece, liners for determining the depth of a slug, and means for maintaining said movable aliner means at a predetermined distance from said fixed piece.
4. In a machine of the class described, the combination of a mold supporting means, a mold cap fixed to said means, a bar fixed to said means, an aliner means, spring means intermediate said bar and said aliner means to urge said aliner means toward said mold cap, and means intermediate said mold cap and said aliner means for maintaining them at a predetermined distance apart.
5. In a machine of the class described, the combination of a mold cap means, an alining means, means intermediate to determine the form of a slug, locking means for assembling all of said means, and latching means for maintaining said locking means in assembled position.
6. In a machine of the class described, the combination of a mold cap, a matrix alining means, resilient means for urging said means toward said cap, spacing members to keep said alining means at a predetermined distance from said cap, means for joining the alining means and spacing members in fixed relation to said mold cap.
7. In a machine of the class described,

the combination comprising a filler member, liner means, a fixed mold cap, each of said before mentioned elements having a plurality of holes, and pin connections adapted 5 to engage combinations of said holes whereby the relation between said liner means and said mold cap may be varied.

8. In a machine of the class described, the combination of mold cap means, liner 10 means, all of said means having holes for their relative adjustment, and a clamping means having pins adaptable to co-operate with combinations of said holes for varying the position of said liner means.

9. In a machine of the class described, the combination comprising a fixed mold for casting type of different font sizes dressed on a line of feet, a fixed mold cap, an aliner rail, resilient means constantly urging said aliner rail toward said fixed cap, and means 20 for maintaining a substantially constant distance between said mold cap and said aliner rail.

10. In a machine of the class described, the combination comprising a mold cap having 25 a plurality of holes, a liner having a plurality of holes spaced at two-thirds the interval between successive holes in said mold cap, and pin connections adapted to 30 maintain a first odd hole in said mold cap

in co-axial alignment with any hole in said liner and to maintain a first even hole in said mold cap in coaxial alignment with any hole in said liner whereby said liner may be positioned in thirteen separate positions in 35 respect to said mold cap within a length equal to four successive spaces defined by successive holes in said mold cap.

11. In a machine of the class described, the combination comprising a mold cap having 40 at one end a plurality of holes, a liner having a plurality of holes spaced at two-thirds the interval between successive holes in said mold cap, and pin connections for maintaining an odd hole in said mold 45 cap in co-axial alignment with either an odd or an even hole in said liner.

12. In a machine of the class described, the combination comprising a mold cap having 50 at one end a plurality of holes, a liner having a plurality of holes spaced at two-thirds the interval between successive holes in said mold cap, and pin connections for maintaining an even hole in said mold cap 55 in co-axial alignment with either an even or an odd hole in said liner.

In testimony whereof I hereunto affix my signature.

JEAN MARTIAL LOBIT.
